Patented May 27, 1919.

UNITED STATES PATENT OFFICE.

JOHN A. EBERLE, OF ST. LOUIS, MISSOURI.

SWING.

1,304,951.

Specification of Letters Patent. Patented May 27, 1919.

Application filed June 19, 1916. Serial No. 104,422.

To all whom it may concern:

Be it known that I, JOHN A. EBERLE, a citizen of the United States of America, a resident of the city of St. Louis, State of Missouri, have invented certain new and useful Improvements in Swings, of which the following is a full, clear, and exact description, reference being had to the accompanying drawing, forming a part of this specification.

My invention relates to improvements in swings, the object being to produce a neat, comfortable and inexpensive swing particularly adapted for the use of infants or children.

Figure I is a front elevation of a swing constructed in accordance with the invention.

Fig. II is a detail view of the elements near the upper end of the swing.

Fig. III is a top or plan view of the swing.

Fig. IV is an enlarged fragmentary section showing one of the coils of the spreader frame and a suspension member secured thereto.

To illustrate the preferred form of the invention, I have shown a seat A in the form of a pocket made of pliable sheet material, such for example as canvas or other fabric and having its upper margins secured to a rigid rectangular seat frame B. The pocket A is a rectangular member having a bottom wall and four side walls, one of the side walls being provided with a pair of limb receiving openings 1 at points between the bottom wall and the rigid rectangular frame B. The upper margins of the pocket are folded over the frame B and stitched, as shown most clearly in Fig. III, so as to secure the pocket to said frame B.

The seat frame B is preferably a continuous wire, turned upwardly at the four upper corners of the seat to form the upper turned wire elements 2 which are exposed at the corners of the seat.

A central hanger ring 3, at the upper end of the swing, is connected to the seat by means of four suspension straps 4, the lower ends of said straps being secured to the upturned wire elements 2 at the corners of the rectangular seat frame B. The four suspension straps are preferably made of two strips of fabric, inserted through the hanger ring 3 and turned near their upper ends to form the loops 5 at the hanger ring. 6 designates rivets passing through the loop members at points near the hanger ring 3.

C designates a rigid rectangular spreader frame, consisting of a single piece of wire coiled at the corners of the frame to produce four eyes 7 through which the four suspension straps are inserted. This spreader frame is secured to the suspension straps 4 by means of short straps 8 attached to the suspension straps at opposite sides of the eyes or coils 7.

The simple rigid rectangular wire frame B may be easily manufactured and combined with the fabric elements of the device, to produce a strong, safe and comfortable child's swing, the rectangular seat pocket A being firmly held by the wire frame B at its four upper margins, and the suspension straps 4 being widely separated by the rigid rectangular spreader frame C.

I claim:—

A child's swing comprising a single rigid rectangular seat frame, a rectangular fabric pocket having its upper margins folded over and secured to said rigid rectangular seat frame, suspension members secured to the corners of said rigid rectangular seat frame, and a rigid rectangular spreader separating said suspension members at points above said rigid rectangular seat frame, the corners of said spreader corresponding to the corners of said rigid rectangular seat frame.

JOHN A. EBERLE.
